Primary Examiner — Philip S Hyder*Assistant Examiner* — Darlington Ly(74) *Attorney, Agent, or Firm* — Sterne, Kessler, Goldstein & Fox P.L.L.C.(57) **CLAIM**

The ornamental design for a soft bicycle bag, as shown and described.

DESCRIPTION

FIG. 1 is a right side elevational view of a soft bicycle bag; FIG. 2 is a left side elevational view thereof; FIG. 3 is a top plan view thereof; FIG. 4 is a bottom plan view thereof; FIG. 5 is a front elevational view thereof; and, FIG. 6 is a rear elevational view thereof. The broken lines in the drawings illustrate portions of the soft bicycle bag that form no part of the claimed design.
